DESIGN FOR A WALL SWITCH PLATE

Jules P. Gits and Joseph A. Gits, Chicago, Ill.

Application August 30, 1944, Serial No. 115,125

Term of patent 14 years

(Cl. D26—13)

To all whom it may concern:

Be it known that we, Jules P. Gits and Joseph A. Gits, citizens of the United States, residing at Chicago, in the county of Cook and State of Illinois, have invented a new, original, and ornamental Design for a Wall Switch Plate, of which the following is a specification, reference being had to the accompanying drawing forming a part thereof.

Figure 1 is a perspective view of the wall switch plate embodying the new design;

Figure 2 is a longitudinal sectional view thereof on the line 2—2 of Figure 1; and

Figure 3 is a cross-sectional view of the same on the line 3—3 of Figure 1.

We claim:

The ornamental design for a wall switch plate, substantially as shown.
